UNITED STATES PATENT OFFICE

BERNARD COOK, OF ROANOKE COUNTY, VIRGINIA

PEDESTAL BINDER FOR LOCOMOTIVE FRAMES

Application filed September 17, 1931. Serial No. 563,340.

My invention relates to certain improvements in pedestal binders for locomotive frames. The purpose of the invention is:

To prevent concentration of stresses in the 5 binder when it is pressed into place on the frame;

To arrange the fitting faces of that part of the pedestal binder which bears against the frames so they can be easily maintained;

10 To arrange the pedestal binder so there will be no possibility of a shoulder wearing on the frame fit of the binder to interfere with the maintenance of the fit between the pedestal binder and the frame, and to make the 15 pedestal binder easy to remove; also other features that will be explained hereafter.

In the accompanying drawing, Figure 1 is an elevation of the pedestal binder.

Figure 2 is a plan view of the pedestal 20 binder.

Figure 3 shows, in elevation, a portion of the locomotive frame taking in that part surrounding one of the axles and shows the pedestal binder in place.

25 Figure 4 is an arrangement of the details of the pedestal binder and pedestal differing from that shown in Figure 3, but serving, in a large measure, the same purpose.

Referring to Figure 3, the locomotive 30 frame is composed of a top rail 1, a bottom rail 2 and the pedestal 3. These pedestals are each side of the opening to receive the axle box. The pedestal binder 4 is placed so as to cover this opening at the bottom and virtually to make the bottom rail continuous.

35 It is very necessary, in order to resist the very heavy forces set up in the locomotive frame, that the contact surfaces 5, between the pedestal binder 4 and the bottom part of the pedestal 3, which parts we will call the pedestal toes, should be very well fitted and should remain so fitted, and at the same time be so arranged that the pedestal binder can be readily removed.

40 Under the heavy working forces of the locomotive it is practically impossible to prevent some movement at the contact faces 5. This brings about wear of the parts and with this wear the pedestal binders become loose.

50 When the pedestal binders become loose,

there is a lack of continuity in the bottom rail 2 of the frame, and this will throw bending stresses in the top rail 1 and in the pedestals 3, causing them to break.

In the ordinary method of fitting pedestal binders to the frame, the tapered contact face is the usual form and the pedestal binder is slotted so as to allow approximately the same clearance between the bottom of the pedestal toes and the bottom of the slot in the binder as is left between the top of the pedestal binder and the bottom rail of the frame similar to location 6, as shown in Figure 3. This clearance allows the pedestal binder to be tightened on the frame by bolts, 55 similar to 9.

In the old method, however, where there are relatively sharp corners in the bottom of the slot in the pedestal binders, very heavy 60 stresses are set up and the pedestal binders are often broken at these sharp corners. In pressing these old form pedestal binders in place, the bottom of the slot in the pedestal binder is often brought close against the toe 65 of the pedestal at the same time the top of the pedestal binder comes in contact with the bottom of the frame rail at a location similar to 6 in Figure 3. This does not allow for the tightening of the pedestal binder by the bolts, similar to 9, nor does it leave an opening 70 for inserting a wedge for forcing off the binder.

75 When the old type pedestal binder is applied and there is clearance left between the bottom of the pedestal toes and the bottom of the slot in the binder, the wear between the contact surfaces of the binder and the pedestal toe produces a slight shoulder. This shoulder forms a high spot which quickly 80 wears off, on account of the small bearing, when the binder is drawn up further on the taper of the pedestal toe, and allows the binder to become loose.

85 On this improved binder the clearance between the bottom of the toe, which is made flat, and the bottom of the slot in the pedestal binder, which is made with a slight curve 7, is deeper than the clearance allowed at the point 6. The ends of the curve 7 are carried 90 further each way than the width of the bot-

tom of the pedestal toe and are terminated by curves of very much shorter radii, reversing entirely the direction of the surface as at the point 8, and in this way making the surface 5 of the pedestal binder so that it will entirely clear the surface 5 of the pedestal toe, where they contact, and allow the toe to reach into the space so that no slight shoulder will be worn on the binder. This will fix the binder so that its surfaces 5 will be fully in contact throughout its whole extent with the surfaces of the pedestal toe.

The contact surface 5 of the pedestal binder being free from and separated from the curved surface 7, will permit the surface 5 of the binder to be built up by the welding process when it becomes worn without any damage to the quality of the metal of the binder in the sections 7 and at the point 8. This building up of the worn surfaces allows the binder to be refinished and refitted as if new. The slight thinning down in the depth of the pedestal binder in the central portion of the surface 7, and the gradual change in the section of the binder at this point, prevents the localizing of stresses in the binder, as is the case where the surfaces have sharp intersections, such as in the old form of pedestal binder. It will minimize the chance of fracture of the pedestal binders.

It is to be noted that in the fitting of these pedestal binders they can be placed by hand, leaving a clearance at the point 6, forcing them in place with the proper pressure, and then having the pedestal binder bolts 9 drawn tight. The form of the pedestal binder at the point 7 is such that it facilitates the springing of the binder under the load of these bolts as the binder is drawn tight, and will bring the surfaces 5 in complete and uniform contact, and at the same time distribute the stresses in the section of the binder at the point 7.

The curved portion in the bottom of the slot in the pedestal binder will prevent this surface from ever coming in contact with the bottom of the toe of the pedestal, so that under every condition there will be sufficient room to enter a wedge to drive the binder off when it is desirable to remove the same, even though the wedging action holds it very tight.

Referring to Figure 4. The parts 5' and 8' are duplicates, in shape and in function, of parts 5 and 8 of Figure 3. The flat surface at 7', Figure 4, in conjunction with surface 10' will serve to keep the surfaces from ever coming together. The curved end extensions 8' of the groove in the pedestal binder 4, used in connection with the plain surface 7', Figure 4, while it may not be the preferred arrangement, will prevent the localizing of stresses at 8', and will permit the building up of the surfaces 5' by the welding process without injury to the quality of the metal of the binder in the section 7' at the point 8',

Figure 4, just as does the arrangement in Figure 3.

In the matter of preventing contact between the bottom of the pedestal and the bottom of the slot in the binder, under all circumstances, the use of the surface 10', Figure 4, serves just as well in conjunction with the surface 7, of Figure 3, as with surface 7', Figure 4.

Having described my invention so that any one familiar with the art can readily use the same and perceive its advantages, I claim:

1. In a locomotive or vehicle frame, the combination of pedestals and a pedestal binder, said binder having a slot receiving and making contact with the toe of each pedestal, said slot having at its bottom a curved surface terminating in additional curves reversing the direction of said surface, said additional curves extending beyond the contact surface between said pedestal toe and said binder. 85

2. In a locomotive or vehicle frame, the combination of pedestals and a pedestal binder, said binder having a slot receiving and making contact with the toe of each pedestal, said slot being recessed at the bottom beyond the contact surfaces between said pedestal toe and said binder so as to provide contact of the binder with the pedestal toe throughout the whole contact surface of the binder. 95

3. In a locomotive or vehicle frame, the combination of pedestals and a pedestal binder, said binder having a slot receiving and making contact with the toe of each pedestal, the bottom of said slot having a curved surface. 100

4. In a locomotive or vehicle frame, the combination of pedestals and a pedestal binder, said binder having a slot receiving and making contact with the sides of the toe of each pedestal, the bottom of the pedestal toe and the bottom of said slot being of different contours to prevent them coming in contact with each other. 105

5. In a locomotive or vehicle frame, the combination of pedestals and a pedestal binder, said binder having a slot receiving and making contact with the toe of each pedestal, said slot being recessed at the bottom beyond the contact surfaces so as to permit the building up of the whole of the contact surfaces by welding without bringing the welding metal in contact with the bottom of the slot. 110

6. A locomotive or vehicle frame pedestal binder, having a slot with contacting sides and a curved bottom. 115

7. A locomotive or vehicle frame pedestal binder, having a slot with contacting sides and a curved bottom, said curved bottom extending beyond said contacting sides. 120

In testimony whereof, I hereunto affix my signature this 14th day of Sept., 1931.

BERNARD COOK.
